MARTIN HEMLEB, OF ELIZABETH, NEW JERSEY, ASSIGNOR TO THE SINGER MANUFACTURING COMPANY, OF ELIZABETH, NEW JERSEY, A CORPORATION OF NEW JERSEY.

REVOLVING-HOOK MACHINE.

Application filed March 1, 1926. Serial No. 91,320.

This invention relates to an improvement in sewing machines of the revolving hook type. In some machines of this type the thread-case has a flange-and-groove connection with the loop-taker which, not infrequently, becomes clogged during the operation of the machine by particles of thread, lint or other obstructions, necessitating disassembling of the parts in order to remove such obstructions before the machine is again in sewing condition.

The invention has for its object a simplified and improved construction of mounting the thread-case upon its loop-taker whereby the objectionable features above referred to are eliminated.

More specifically, the invention has for its object an improved mounting of the thread-case upon its loop-taker so that removal of the thread-case can be readily effected when it becomes necessary to remove any lint, thread-ends or other obstruction which may have lodged between the supporting ledge of the loop-taker and thread-case during the operation of the machine or which may have been deposited in the cavity of the sewing machine bed-plate or work-support in which the lower thread-handling devices are located.

In the preferred form of the improvement the thread-case is of disk form with an open topped bobbin-cavity having a side wall projecting above said body notched to expose the upper flange of a contained bobbin, the bobbin-cavity being arranged eccentrically to the axis of the loop-taker or hook farthest from the needle-path so as to expose the full area of the bobbin-cavity laterally of the adjacent edge of the throat-plate for easy removal and insertion of the bobbin. The thread-case is removably mounted upon a supporting ledge of a cup-shaped loop-taker and restrained against rotation by a fixed holding or positioning plate secured to the sewing machine bed-plate. To prevent accidental displacement of the thread-case from the loop-taker, while the bed-plate slide is shifted, to replace a bobbin or while the sewing machine is tilted upon its hinges in a drop-head cabinet or portable base, a locking plate, overhanging the bearing flange of

the thread-case, is provided. This plate is secured upon one end by a pivot-screw to the sewing machine bed-plate or work-support while its other end is notched to receive a stop and fastening screw also entering the bed-plate. The positioning plate and locking plate overlie different portions of the bearing flange and normally confine the thread-case in its operative position upon the loop-taker. When the stop-screw is loosened the locking plate may be readily swung to one side to clear the thread-case which when tilted, may be easily removed from the loop-taker for convenience in clearing the loop-taker cavity and loop-taker of any lint or thread-ends which may have lodged thereon so as to clog the free movement of the loop-taker or which may have accumulated in the cavity of the sewing machine bed.

In the accompanying drawings, Fig. 1 is an elevation of a portion of a sewing machine to which the improved thread-case mounting is applied, the lower thread-handling mechanism being partly shown in section through the line A—B of Fig. 2. Fig. 2 is a top plan view representing the lower thread-handling mechanism with the bed-slide removed showing the holding and locking plate in operative position. Fig. 3 is a perspective detail of the loop-taker, partly in section, with thread-case and holding and locking plate and Fig. 4 is a perspective detail of the holder.

Referring to the drawings 1 denotes the sewing machine bed-plate or work-support having a depending bearing lug 2 for the horizontal shaft 3, on the end of which is secured the bevel gear 4 meshing with the bevel gear 5 on the vertical loop-taker shaft 6 journaled in the bearing bushing 7 sustained in the depending member 8 of the work-support by the set-screw 9. The collar 10 secured upon the vertical shaft 6 by the set-screw 11 prevents longitudinal displacement of the shaft in its bearing. A split case 12 encloses the bevel gears 4 and 5.

Secured upon the upper end of the vertical shaft 6 by means of a central screw 13 and eccentric pin 14 is the cup-shaped hook or loop-taker 15 having an inwardly

extending loop-seizing beak 16 and the usual throat 17 and loop-detaining shoulder 18. The upper edge of the hook or loop-taker 15 is provided with an external flange 19 5 affording a ledge upon which rests the laterally extending disk or bearing flange 20 of the thread-case 21 of which the open topped cup-shaped body provides a cavity for the bobbin 22 disposed eccentrically to 10 the loop-taker axis. The bearing flange 20 of the thread-case 21 has two substantially parallel faces of which the inner face rests upon the external flange 19 of the loop-taker 15 while the other of said faces is exposed 15 beyond the bearing flange 19 of the loop-taker. The thread-case is thus removably sustained by the loop-taker. The wall of the cavity of the thread-case 21 extends upwardly above the disk 20 and is provided in its 20 upper edge with diametrically opposed finger notches 23 which extend below the upper flange of the bobbin 22 to enable the latter to be readily grasped by the operator for removal when the bobbin is in normal operative 25 position in the thread-case. The up-standing wall of the thread-case 21 is provided with the usual form of bobbin-thread tension spring 24.

By reference more particularly to Fig. 2, 30 it will be observed that the thread-case 21 is so disposed within the field of action of the loop-taker 15 that the entire bobbin cavity is exposed laterally beyond the edge of the throat-plate 25 so that by merely withdrawing bed-slide 26, normally covering the bobbin-cavity, the bobbin is readily accessible 35 to the operator for removal or replacement by another bobbin.

Secured upon the disk 20 of the thread-case 40 is the pivotally mounted spring-pressed cushioning finger 27 entering a notch 28 in a fixed holding or positioning plate 29 secured by a screw 30 in a slot 31 in a depression of the work-support 1 beneath the bed-slide 26. The holding plate, which restrains the thread-case 21 against turning with the loop-taker 15, is provided with a portion 32, 45 adjacent the spring-pressed finger 27, which overhangs one portion of the bearing flange of the thread-case 21 and normally confines the latter in its position upon the loop-taker during sewing operation. Sufficient thread-clearance is provided in the notch 28 of the holding plate 29 entered by the cushioning finger 27 to afford easy escape of the needle-thread loop as it is cast about the mass of 50 under thread upon the bobbin 22.

In order to prevent accidental displacement 60 of the thread-case 21 from the loop-taker during the removal of a bobbin therefrom, or while the bed-slide 26 is withdrawn and the sewing machine is tilted upon its hinges in a drop-head cabinet or portable case, a locking plate 33 is provided. This 65 plate is secured at one end upon the pivot

screw 34 to the sewing machine work-support 1 in the depression beneath the bed-slide 26 while its other end is notched at 35 to receive a stop and fastening screw 36 also entering the depression in the work-support. The locking plate is further provided with a lug 37 to assist in shifting the plate from operative to inoperative position. As will be observed by reference to Fig. 2 70 the locking plate 33 overhangs another portion of the bearing flange 20 of the thread-case 21 at a point diametrically opposite the overhang 32 of the holding or positioning plate 29 and thereby effectually prevents accidental displacement of the thread-case 21 75 from the loop-taker 15. By reference to Fig. 1 it will also be observed that both the holding plate 29 and the locking plate 33 are secured to the sewing machine bed or work-plate below the level of the throat-plate 25 and below the plane of the uppermost portion of the upstanding notched walls of the thread-case. Sufficient thread-clearance is provided between the thread-case 21 and the overhanging portion of the 80 locking plate 33 to afford free passage of the needle-thread loop.

When it is desired to remove the thread-case 21 from the loop-taker 15 for convenience in clearing the loop-taker or loop-taker cavity in the work-support of any lint or thread-ends which may have accumulated thereon, the holding screw 36 is loosened and the locking plate 33 is swung to the dotted line position shown in Fig. 2 by engagement of the lug 37 provided for the purpose whereupon the thread-case, when tilted, may be readily removed from the loop-taker.

The machine is provided with the usual feed-dog 38 carried by the feed-bar 39 opposed to which is the usual presser-foot 40 secured by the screw 41 upon the presser-bar 42. Secured to the needle-bar 43 by the needle-clamp 44 is the needle 45 which descends within the field of action of the loop-taker 21 in the formation of stitches in the usual and well known manner.

It will be observed that the thread-case 21 is loosely supported upon the open-topped loop-taker 15 thereby facilitating easy removal and replacement of the thread-case from the looper without the necessity of disassembling any portion of the lower thread-handling mechanism. It will be further observed that the locking plate 33 insures against accidental displacement of the thread-case 21 from the loop-taker 15 when a bobbin of thread is removed from the thread-case or when the thread from the bobbin is passed beneath the tension-spring 115 24. The locking plate 33 further maintains the thread-case 21 in operative position upon its loop-taker if, after the bed-slide 26 is withdrawn, the sewing machine should be tilted upon its hinges in a drop-head cabinet 120 125 130

or portable base for access to the mechanism beneath the work-support.

Having thus set forth the nature of the invention, what I claim herein is:—

- 5 1. In a sewing machine, in combination with a cup-shaped rotary hook and a thread-case with a bearing flange having one of two substantially parallel faces in external engagement with the rim of said hook and the other of said faces exposed beyond said hook, a stationary holder overlying a portion of 40 said exposed face of the bearing flange and having rotation restraining engagement with said thread-case, and a locking plate overlying another portion of said exposed face of the bearing flange and manually movable to uncover said bearing flange for 45 permitting ready removal of the thread-case, said holder and locking plate being mounted on the work-support below the level of the throat-plate.
- 10 2. In a sewing machine, in combination, a work-support, a throat-plate mounted thereon, a cup-shaped rotary hook, a thread-case with a bearing flange having one of two substantially parallel faces in external engagement with the rim of said hook and the other of said faces exposed beyond said hook, a stationary holder overlying a portion of 50 said exposed face of the bearing flange and having rotation restraining engagement with said thread-case and a locking plate overlying another portion of said exposed face of the bearing flange and manually 55 retractile to uncover said bearing flange for permitting ready removal of the thread-case, said holder and locking plate being disposed below the plane of the uppermost portion 60 of the thread-case.
- 15 3. In a sewing machine, in combination, a work-support, a throat-plate mounted thereon, a cup-shaped rotary hook, a thread-case with a bearing flange having one of two substantially parallel faces in external engagement with the rim of said hook and the other of said faces exposed beyond said hook, a stationary holder overlying a portion of 65 said exposed face of the bearing flange and having rotation restraining engagement with said thread-case and a locking plate overlying another portion of said exposed face of the bearing flange and manually 70 retractile to uncover said bearing flange for permitting ready removal of the thread-case, said holder and locking plate being disposed below the plane of the uppermost portion 75 of the thread-case.
- 20 4. In a sewing machine, in combination, a work-support, a throat-plate mounted thereon, a cup-shaped rotary hook, a thread-case with a bearing flange having one of two substantially parallel faces in external engagement with the rim of said hook and the other of said faces exposed beyond said hook, a stationary holder overlying a portion of 80 said exposed face of the bearing flange and having rotation restraining engagement with said thread-case and a locking plate overlying another portion of said exposed face of the bearing flange and manually 85 retractile to uncover said bearing flange for permitting ready removal of the thread-case, said holder and locking plate being disposed below the plane of the uppermost portion 90 of the thread-case.

In testimony whereof, I have signed my name to this specification.

MARTIN HEMLEB.
